US00D575898S

(12) **United States Design Patent**
Tran et al.

(10) **Patent No.:** US D575,898 S
(45) **Date of Patent:** ** Aug. 26, 2008

(54) **END PORTION OF A LIGHTING FIXTURE**

(75) Inventors: **Michael Trung Tran**, Oakland, CA (US); **Frank A. Friedman**, Mill Valley, CA (US); **Peter Y. Y. Ngai**, Alamo, CA (US)

(73) Assignee: **Acuity Brands, Inc.**, Atlanta, GA (US)

(**) Term: **14 Years**

(21) Appl. No.: **29/286,508**

(22) Filed: **May 8, 2007**

(51) **LOC (8) Cl.** 26-99

(52) **U.S. Cl.** D26/113

(58) **Field of Classification Search** D26/118, D26/76, 120, 121, 77, 141, 128, 78, 3, 88, D26/85, 87, 65, 67, 68, 81, 84, 155, 145, D26/142, 113, 138, 57, 72, 73, 75, 82, 89, D26/93, 109, 108, 119, 143, 152; D11/90; D25/124; D10/114; D13/135, 134; 362/298, 362/555, 576, 581, 147, 151, 153, 217, 219, 362/235, 241, 279, 290, 297, 325, 404, 405, 362/410, 800

(57) **CLAIM**

The ornamental design for an end portion of a lighting fixture, as shown and described.

DESCRIPTION

FIG. 1 is a bottom perspective view of an end portion of a lighting fixture showing our new design;

FIG. 2 is a right side elevational view thereof, the left side being a mirror image;

FIG. 3 is a bottom plan view thereof;

FIG. 4 is a top plan view thereof;

FIG. 5 is an end elevational view thereof;

FIG. 6 is an enlarged end elevational view thereof; and,

FIG. 7 is an enlarged right side elevational view thereof.

The broken lines immediately adjacent solid lines in FIG. 4 represent the bounds of the claimed design while all other broken lines are directed to environment and are for illustrative purposes only; the broken lines form no part of the claimed design.

1 Claim, 5 Drawing Sheets
